(57) **CLAIM**

The ornamental design for a screed plate, as shown and described.

DESCRIPTION

FIG. 1 is a front, top, right side perspective view of a screed plate showing our new design;

FIG. 2 is a rear, bottom, right side perspective view of the design shown in FIG. 1;

FIG. 3 is a bottom view of the design shown in FIG. 1;

FIG. 4 is a front view of the design shown in FIG. 1;

FIG. 5 is a rear view of the design shown in FIG. 1;

FIG. 6 is a left side view of the design shown in FIG. 1;

FIG. 7 is a right side view of the design shown in FIG. 1; and,

FIG. 8 is a top view of the design shown in FIG. 1.

The evenly-spaced broken lines in the Figures illustrate portions of the screed plate that form no part of the claimed design. The dash-dot-dash broken lines in the Figures illustrate the boundary of the claimed design which forms no part thereof.

1 Claim, 8 Drawing Sheets
